(57) **CLAIM**

The ornamental design for a lighting fixture, as shown and described.

DESCRIPTION

FIG. 1 is a perspective view from above of the lighting fixture; FIG. 2 is a perspective view from below of the lighting fixture of FIG. 1;

FIG. 3 is a right-side elevation of the lighting fixture of FIG. 1, the left-side elevation view being a mirror image thereof; FIG. 4 is a bottom plan view of the lighting fixture of FIG. 1; FIG. 5 is a top plan view of the lighting fixture of FIG. 1; FIG. 6 is a front elevation of the lighting fixture of FIG. 1; FIG. 7 is a rear elevation of the lighting fixture of FIG. 1; FIG. 8 is a perspective view from above of a second embodiment of the lighting fixture, the primary difference being the inclusion of a middle portion in a forward region of the fixture;

FIG. 9 is a perspective view from below of the lighting fixture of FIG. 8;

FIG. 10 is a right-side elevation of the lighting fixture of FIG. 8, the left-side elevation view being a mirror image thereof; FIG. 11 is a bottom plan view of the lighting fixture of FIG. 8; FIG. 12 is a top plan view of the lighting fixture of FIG. 8; FIG. 13 is a front elevation of the lighting fixture of FIG. 8; and,

FIG. 14 is a rear elevation of the lighting fixture of FIG. 8. The phantom lines are provided for illustrative purposes only and form no part of the claimed design.

1 Claim, 12 Drawing Sheets
